UNITED STATES PATENT OFFICE.

ADOLPHUS W. RICH, OF MILWAUKEE, WISCONSIN.

DESIGN FOR A LOW SHOE.

SPECIFICATION forming part of Design No. 33,443, dated October 23, 1900.

Application filed September 24, 1900. Serial No. 31,004. Term of patent 7 years.

To all whom it may concern:

Be it known that I, ADOLPHUS W. RICH, a citizen of the United States, residing at Milwaukee, in the county of Milwaukee and State 5 of Wisconsin, have invented and produced a new and original Design for Low Shoes, of which the following is a specification, reference being had to the accompanying drawings, forming a part thereof.

10 Figure 1 is a side view of a shoe of my new design; and Fig. 2 is a front view of the same, the lace being removed in both figures and one of the lacing-flies being folded back in Fig. 2.

15 As shown in the drawings, the leading or material feature of my design consists of an inset inverted-heart-shaped or shield-shaped piece *a* over the instep, extending from the vamp *b* to the opening in the top *c*. The inset piece *a* is made of material which con-

trasts with that of the vamp and top, and it is stitched to the overlying edges of the vamp *b* and of the top *c*. The seams between the inset piece *a* and the top *c* extend in diverging curves from the opening in the top to 25 the seam between the top and vamp and constitute lines of demarcation between the top and the lacing-flies *d* *d*, with the edges of which they run substantially parallel.

Having thus described my invention, what 30 I claim as new, and desire to secure by Letters Patent, is—

The design for a low shoe, substantially as herein shown and described.

In witness whereof I hereto affix my signature in presence of two witnesses.

ADOLPHUS W. RICH.
